UNITED STATES PATENT OFFICE.

MARION A. ANDREWS, OF YUMA, ARIZONA.

DOOR FASTENER.

Application filed January 11, 1923. Serial No. 611,960.

To all whom it may concern:

Be it known that I, MARION A. ANDREWS, a citizen of the United States, residing at Yuma, in the county of Yuma and State of 5 Arizona, have invented new and useful Improvements in Door Fasteners, of which the following is a specification.

This invention relates to fastening devices and more particularly to automobile door 10 fasteners.

It is an object of the present invention to provide an extremely simple, substantial and effective means for latching automobile doors in closed position and to provide for 15 the ready releasing of the latch. Another object of the invention is to provide a locking device having but a single operating element for latching and for releasing the door, and another object is to provide a locking 20 device operative to prevent rattling of the door.

Other objects and advantages will be made manifest in the following specification of an embodiment of the invention ill- 25 lustrated in the accompanying drawings, wherein—

Figure 1 is a perspective of a portion of a body of an automobile showing the door in open position to illustrate the latching ele- 30 ment.

Fig. 2 is a perspective of the detached yieldable latch.

Fig. 3 is a face elevation of a portion of the door style in which the latch keeper is 35 countersunk.

Fig. 4 is a section on line 4—4 of Fig. 3.

Fig. 5 is a sectional view showing the parts in coacting position as engaged during the closing of the door.

Fig. 6 is a vertical section showing the position of latching parts after the door is closed.

Fig. 7 is a perspective of the mortised door style with the latch plate removed and 45 showing the latch in perspective.

Fig. 8 is a perspective of the latch keeper secured on the body frame.

The present invention consists of a sub- 50 stantially straight push rod or stem 2, the upper end of which is provided with a button 3 for access in the upper edge of a door D, for instance an automobile door. The latch 2 is slidably mounted in a bore 4 in the door structure, the upper of the door being 55 enlarged at 5 to receive the button 3. Below the lower end of the latch stem is arranged

an expansile spring 7 normally thrusting the latch to uppermost position and serving to move a block-like part 8 into engagement with a shoulder 9 formed in a mortise or 60 pocket in the door structure and in which the block 8 is vertically slidable and is guided and is prevented from having rotary action. The mortised latch block is substantially covered by a simple section of 65 casing 10 which is provided in its face with an aperture 11. On one side of the latch block 8 and exposed in the aperture 11 of the casing is a locking nib or hook 12 curved upwardly and inwardly from the face of the 70 block.

Secured to the edge of a style 14 of the body frame of the vehicle is a countersunk keeper plate 15 which may be fastened as by screws 16, and angularly projecting from 75 the rear of this plate is a flange 17. Projecting forwardly from this flange is a stout downwardly projecting hook 18, the lower outer corner of which is curved or beveled downwardly and rearwardly at 18^a, and this 80 is adapted to be engaged by the curved front face of the latch nib or hook 12 when the door D is swung closed. The latch stem with the block will yield downwardly as the latch nib 12 engages the keeper hook 18 85 and will snap up into interlocking position with the hook 18 thus fastening the door in closed position.

In alignment with and below the keeper hook 18 is a lug 19 rigid with the flange 17 90 of the keeper plate and this lug 19 is adapted to swing in under an inwardly projecting shoulder 20 provided on the face of the latch casing 10, as clearly shown in Fig. 3; the lug 19 being engaged by the 95 lower corner of the shoulder 20 and the lower edge of the aperture 11 and, therefore, holding the door against material vertical play or vibration.

To open the door it is only necessary to 100 press down the push button 3 which will force the latch down against its spring 7 after which the door may be swung open and the latch end released to resume its normal position.

Further embodiments, modifications and variations may be resorted to within the spirit of the invention as here claimed.

What is claimed is:

1. In a closure fastening device, a stem 110 having intermediate its length a block for preventing rotation of the stem in its mount-

ing, said block having a latching part, and a keeper including a plate attachable to a supporting element, the keeper having a hook parallel to said plate and engageable by the 5 said part.

2. In a closure fastening device, a stem having intermediate its length a block preventing rotation of the stem in its mounting, said block having a latching part, a keeper 10 including a plate attachable to a supporting element, the keeper having a hook parallel to said plate and engageable by the said part, a casing section covering the latching block and having an aperture to receive 15 the keeper hook, said casing section having a shoulder at one side of the aperture, and a lug combined with the keeper plate to enter

said aperture between said shoulder and a contiguous edge of the aperture and whereby play of the closure when latched is obviated. 20

3. In a closure fastening device, a stem having a button at its upper end and having intermediate its length a block for preventing rotation of the stem in its mounting, said block having a latching part, and a keeper including a plate attachable to a supporting element, the keeper having a hook parallel to said plate and engageable by the 25 said part. 30

In testimony whereof I have signed my name to this specification.

MARION A. ANDREWS.
